HYDRAULIC CYLINDER

Bruce Buckley, Sioux City, Iowa, assignor to Prince Manufacturing Corporation, Sioux City, Iowa, a corporation of Iowa

Filed Sept. 30, 1963, Ser. No. 312,608

14 Claims. (Cl. 92—128)

Hydraulic cylinders are widely used in many different fields of activities. Perhaps the most common difficulty associated with these hydraulic cylinders is the method of securing the cylinder heads to the cylinder. Many devices have been advanced which have not been altogether successful in meeting the above problem. One method of securing the cylinder head to the cylinder is by a threaded insert. This threaded insert is very expensive to manufacture and when the cylinder is exposed to pressure, the threaded insert has a tendency to unthread. Another method of securing a cylinder head to the cylinder is by a snap ring device. These snap ring devices have a tendency to cause swelling of the cylinder and do not hold the cylinder head securely to the cylinder. The snap ring devices also have a tendency to squeeze into the center of the cylinder when pressure is applied to the device. In addition to the above shortcomings of the heretofore mentioned devices, said devices are difficult to assemble and disassemble and usually need special tools for such assembly and disassembly.

Therefore, an object of my invention is to provide a device which may be easily assembled and disassembled without special tools.

A further object of my invention is to provide a device which will adequately hold extremely great thrust loads.

A further object of my invention is to provide a device which will secure the cylinder head tightly to the cylinder.

A further object of my invention is to provide a cylinder head which is locked positively in place.

A further object of my invention is to provide a device which will prevent a lock ring from squeezing in toward the center of the cylinder.

A further object of my invention is to provide a device which is economical of manufacture, durable in use, and refined in appearance.

These and other objects will be apparent to those skilled in the art.

This invention consists in the construction, arrangements, and combination of the various parts of the device, whereby the objects contemplated are attained as herein-after more fully set forth, specifically pointed out in the claims, and illustrated in the accompanying drawing, in which:

FIG. 1 is a perspective view of the device;

FIG. 2 is an enlarged scale cross-sectional view of the device as viewed on line 2—2 of FIG. 1;

FIG. 3 is a partial side elevational view of the device, as viewed on line 3—3 of FIG. 2, with portions thereof cut away to more fully illustrate the assembled device;

FIG. 4 is a partial side elevational view of the device with portions thereof cut away to illustrate the first step in disassembling the device;

FIG. 5 is a partial side elevational view of the device with portions thereof cut away to illustrate the second step in disassembling the device;

FIG. 6 is a partial side elevational view of the device with portions thereof cut away to illustrate the third step in disassembling the device;

FIG. 7 is a partial cross-sectional view of the device illustrating the third step in disassembling the device;

FIG. 8 is a partial side elevational view of the device with portions thereof cut away to illustrate the fourth step in disassembling the device;

2

FIG. 9 is an end elevational view of the locking ring; and

FIG. 10 is a side elevational view of the locking ring.

I have used the numeral 10 to generally designate a hydraulic cylinder which has a permanently normally closed end and an open end. Hydraulic cylinder 10 includes a cylindrical casing 12, a fluid chamber 14, and ports 20 which are secured to casing 12 and in communication with fluid chamber 14. Cylindrical casing 12 includes

10 outer casing wall 16 and inner casing wall 18. A piston (not shown) is slidably mounted within cylindrical casing 12 and secured at one end to a piston rod 22. A cylinder head 24 is slidably mounted on piston rod 22 within casing 12. Concentric grooves 26 in the inner casing wall

15 18 are located adjacent to the open end of casing 12 and are adapted to embrace locking ring 28, said locking ring 28 being comprised of ring segments 30, 32 and 34. Ring segment 30 includes straight parallel edges 50 and 52, an outer peripheral edge 54 and an inner peripheral edge 56.

20 Ring segment 32 has one end thereof terminating in a straight edge 58 which is complementary to the straight edge 50 of ring segment 30, an outer peripheral edge 60 and inner peripheral edge 62, the straight edge 50 being tangentially disposed with respect to the inner peripheral edge 62.

25 Ring segment 34 has one end terminating in a straight edge 64 which is complementary to the straight edge 52 of ring segment 30, an outer peripheral edge 66 and an inner peripheral edge 68, the straight edge 64 being tangentially disposed with respect to the inner peripheral edge 68.

30 Outer peripheral edges 54, 60 and 66 of ring segments 30, 32 and 34 are adapted to engage the concentric grooves 26 in casing 12. The structure of ring segments 30, 32 and 34 is such that when ring segments 32 and 34 are engaged in concentric grooves 26 of casing 12, ring segment 30 may be engaged in operating position or disengaged from operating position without moving ring segments 32 and 34. The straight edge 58 of

35 ring segment 32, being complementary to straight edge 50 of ring segment 30, and straight edge 64 of ring segment 34 being complementary to straight edge 52 of ring segment 30, permits engagement or disengagement of ring segment 30 without the necessity of moving ring segments 32 and 34. When ring segment 30 is engaged in operating position the abutment of straight edge 52 against

40 straight edge 64 securely holds ring segments 32 and 34 in operating position.

A reduced diameter portion 36 of cylinder head 24 is adapted to engage locking ring 28, said engagement limiting the outwardly slidable movement of the cylinder head

50 24 and also serves to hold locking ring 28 in operating position. Reduced diameter portion 36 has a concentric groove 38 which is adapted to embrace retaining ring 40. The retaining ring 40 engages the outer edge of locking ring 28 and limits the inwardly slidable movement of cylinder head 24. Concentric grooves 42, which are located

55 on the outer circumference of cylinder head 24, are adapted to receive sealing rings 44. A plurality of sealing rings 46 are inserted into concentric grooves 48 of cylinder head 24.

60 The hydraulic cylinder 10 operates in the general manner of the majority of hydraulic cylinders. Fluid is introduced into fluid chamber 14 through ports 20 by means of an external pump arrangement. The fluid causes the piston rod 22 to slidably move within the hydraulic cylinder. This slidable movement of the piston rod 22 may

65 perform various tasks. The very heart of this device is in the structure of the cylinder head 24 and the means by which the cylinder head is secured to and removed from the hydraulic cylinder 10.

66 70 As fluid pressure is applied to the cylinder 24 from within the fluid chamber 14, sealing rings 44 and 46 prevent the fluid from escaping from the cylinder. The lock-

ing ring 28 which engages concentric grooves 26 in the inner wall 18 and also engages the reduced diameter portion 36 of cylinder head 24 prevents the cylinder head 24 from slidably moving outwardly. The retaining ring 40, which is mounted in concentric groove 38 of cylinder head 24, embraces the outer edge of locking ring 28 and prevents the cylinder head 24 from slidably moving inwardly.

To remove the cylinder head 24 from hydraulic cylinder 10 the procedure is as follows. The retaining ring 40 is removed from concentric groove 38 by means of a small screwdriver or other pointed device. Cylinder head 24 is then slidably moved inwardly in casing 12 until the cylinder head 24 clears locking ring 28. Locking ring 28 is then removed by moving ring segment 30 towards the center of the ring until the ring segment 30 is disengaged from concentric grooves 26 in inner wall 18. Straight edge 58 of ring segment 32, which is complementary to straight edge 50 of ring segment 30, and straight edge 64 of ring segment 34, which is complementary to straight edge 52 of ring segment 30, permits ring segment 30 to be moved toward the center of locking ring 28 without moving ring segments 32 and 34. The ring segment 30 is then removed outwardly from the device. Ring segments 32 and 34 are then independently disengaged from concentric grooves 26 by moving them in a direction towards the center of the cylinder and are then removed from the device through its open end. The cylinder head 24, piston rod 22 and the piston are removed from the casing and the unit is then fully disassembled. The assembly of the unit would be accomplished by merely reversing the above described steps of disassembly.

It is therefore seen that the device will accomplish at least all of its stated objectives.

Some changes may be made in the construction and arrangement of my hydraulic cylinder without departing from the real spirit and purpose of my invention, and it is my intention to cover by my claims, any modified forms of structure or use of mechanical equivalents which may be reasonably included within their scope.

I claim:

1. In a cylinder device, an elongated hollow cylindrical casing having one permanently normally closed end and an open end, a piston slidably mounted within said casing, a piston rod secured to said piston, a cylinder head slidably mounted on said piston rod within said casing, a concentric groove within said cylinder casing adjacent to its open end, a locking ring mounted in said groove and protruding therefrom to engage said cylinder head and to limit the outwardly slidable movement of said cylinder head, said locking ring being comprised of a plurality of independent parts detachably held in said groove by said cylinder head, and at least one fluid port on said casing and in communication with the interior thereof.

2. In a cylinder device, an elongated hollow cylindrical casing having one permanently normally closed end and an open end, a piston slidably mounted within said casing, a piston rod secured to said piston, a cylinder head slidably mounted on said piston rod within said casing, said cylinder head including at least one groove extending around the outer circumference of the cylinder head with a sealing ring mounted therein, a bore passing substantially through the center of the cylinder head with a plurality of grooves in the periphery thereof and sealing rings mounted therein, a concentric groove within said cylinder casing adjacent to its open end, a locking ring mounted in said groove and protruding

therefrom to engage said cylinder head and to limit the outwardly slidable movement of said cylinder head,

said locking ring being comprised of a plurality of independent parts detachably held in said groove by said cylinder head, and at least one fluid port on said casing and in communication with the interior thereof.

3. In a cylinder device, an elongated hollow cylindrical casing having one permanently normally closed end and an open end, a piston slidably mounted within said casing, a piston rod secured to said piston, a cylinder head slidably mounted on said piston rod within said casing,

said cylinder head including at least one groove extending around the outer circumference of the cylinder head with a sealing ring mounted therein, a bore passing substantially through the center of the cylinder head with a plurality of grooves in the periphery thereof and sealing rings mounted therein, the forward end of said cylinder head being of a reduced diameter and adapted to embrace the inner edge of said locking ring with a groove extending around the circumference of the reduced diameter portion at a right angle to the longitudinal axis of the cylinder head, and a retaining ring mounted in said groove and protruding therefrom to engage said cylinder head and locking ring and to limit the inwardly slidable movement of said cylinder head, a concentric groove within said cylinder casing adjacent to its open end,

a locking ring mounted in said groove and protruding therefrom to engage said cylinder head and to limit the outwardly slidable movement of said cylinder head,

said locking ring being comprised of a plurality of independent parts detachably held in said groove by said cylinder head,

and at least one fluid port on said casing and in communication with the interior thereof.

4. The structure of claim 3 wherein the locking ring includes at least three ring segments, the outer edges of which are adapted to be received in the concentric groove in said cylinder casing adjacent its open end, the inner edges of said locking ring segments being adapted to embrace the reduced diameter portion of the cylinder head.

5. The structure of claim 3 wherein the locking ring is substantially circular in shape when positioned in said concentric groove, said locking ring being comprised of three independent ring segments, the ends of said ring segments being shaped in such a manner to permit one of said segments to be independently moved inwardly toward the center of said casing without moving said other segments when said cylinder head is withdrawn from engagement with said locking ring.

6. The structure of claim 3 wherein the locking ring is substantially circular in shape when positioned in said concentric groove, said locking ring being comprised of three independent ring segments, and one of said ring segments engaging the other ring segments to maintain said other ring segments within said concentric groove.

7. In a cylinder device, an elongated hollow cylindrical casing having one permanently normally closed end and an open end, a piston slidably mounted within said casing, a piston rod secured to said piston, a cylinder head slidably mounted on said piston rod within said casing, a concentric groove within said cylinder casing adjacent to its open end, a locking ring mounted in said groove and protruding therefrom to engage said cylinder head and to limit

the outwardly slidable movement of said cylinder head,
said locking ring being comprised of a plurality of independent parts detachably held in said groove by said cylinder head,
at least one fluid port on said casing and in communication with the interior thereof,
and a concentric groove on one end of said cylinder head with a retaining ring mounted therein and protruding therefrom, to engage said locking ring and to limit the inwardly slidable movement of said cylinder head.

8. In a cylinder device,
an elongated hollow cylindrical casing having one permanently normally closed end and an open end,
a piston slidably mounted within said casing,
a piston rod secured to said piston,
a cylinder head slidably mounted on said piston within said casing,
a concentric groove in said cylinder casing adjacent to its open end,
a locking ring mounted in said concentric groove and protruding therefrom to engage said cylinder head and to limit the outwardly slidable movement of said cylinder head,
said locking ring being comprised of a plurality of independent parts detachably held in said groove by said cylinder head,
and at least one fluid port on said casing and in communication with the interior thereof.

9. The structure of claim 8 wherein the locking ring includes at least three ring segments, the outer edges of which are adapted to be received in the concentric groove in said cylinder casing adjacent its open end.

10. The structure of claim 8 wherein said locking ring is comprised of three ring segments, one of said ring segments having straight parallel edges. 35

11. The structure of claim 8 wherein said locking ring is comprised of three ring segments, one of said ring

segments having straight parallel edges; said other two ring segments having at least one end thereof terminating in a straight edge complementary to one of the two straight edges of said first ring segment.

- 5 12. The structure of claim 8 wherein said locking ring is comprised of three ring segments, one of said ring segments having straight parallel edges; said other two ring segments having at least one end thereof terminating in a straight edge complementary to one of the two straight edges of said first ring segment; said two other ring segments being substantially identical but being normally positioned in diametrically opposite and symmetrical positions within said concentric groove.
- 10 15 13. The structure of claim 8 wherein said locking ring is comprised of three ring segments, one of said ring segments having straight parallel edges; said other two ring segments having at least one end thereof terminating in a straight edge complementary to one of the two straight edges of said first ring segment; said two other ring segments being substantially identical but being normally positioned in diametrically opposite and symmetrical positions within said concentric groove; said two other ring segments having inner circular peripheral edges with the straight end edges thereof being tangentially disposed with respect to said circular peripheral edges.
- 20 25 14. The structure of claim 8 wherein said locking ring is comprised of three ring segments, one of said ring segments having straight parallel edges and providing less than one-half the periphery of said locking ring.
